SCALER FOR ATOMIC INSTRUMENTATION

Hugh F. Stoddart, Sudbury, Mass., assignor to Baird-
Atomic, Inc., Cambridge, Mass., a corporation of
Massachusetts

Filed May 18, 1959, Ser. No. 55,960

Term of patent 14 years

(Cl. D52—6)

FIG. 1

FIG. 2

FIG. 3

FIG. 1 is a front elevation of a scaler for atomic instrumentation, showing my new design;

FIG. 2 is a top plan view thereof; and

FIG. 3 is a side elevation thereof.

The undisclosed side of the scaler is substantially the same in appearance as the side shown and the rear is plain. The essential features of the design reside in the portions shown in full lines.

I claim:

The ornamental design for a scaler for atomic instrumentation, as shown and described.
